LATCHING AND CLOSING MEANS FOR
RAILWAY CAR HOPPER DOORSGeorge B. Dorey, Westmount, Quebec, Canada,
assignor to Enterprise Railway Equipment
Company, Chicago, Ill., a corporation of Illinois

Application December 23, 1949, Serial No. 134,630

3 Claims. (Cl. 105—308)

1

This invention relates to improved latching means for the doors of railway hopper cars for moving the doors from preliminary partly closed to fully closed position by movement of latching means which are also operable for retaining the doors in fully closed position.

The invention is more especially adapted for use with a pivotally suspended door arranged to meet in closed position with a sloping floor and form therewith a V-shaped hopper. In such construction it has been proposed to employ a plunger type of latch carried by the door and arranged normally to project beyond the swinging edge of the latter for engagement with a keeper carried by the sloping floor of the hopper. The operation of such devices in the past has necessitated the use of cumbersome keepers with forwardly and downwardly inclined projecting runways for displacing the plunger latch from its projected position as the door is moved to closed position, thereby restricting the use of conveyors beneath the hopper for the rapid and economical handling of lading.

In the type of car with which my invention is primarily concerned it is important that the V-shaped hoppers be placed at a low level in the car body in order to maintain a low center of gravity and also provide for maximum carrying capacity. To this end the apices of the hoppers are located in close proximity to the rails and it is therefore necessary that the latch parts which are normally positioned below the hopper be either of such proportions as to infringe upon the clearance limits or on the other hand be of such small proportions as to impair the efficiency and security of the latching means.

The object of this invention, among others, is the attainment of a construction which will overcome the deficiencies above set forth and to this end there is provided an improved plunger type of latch and cooperating shouldered keeper with means extraneous to said keeper for retracting the latch by movement of the door. Other objects are: To provide an improved construction for supporting the door in closed position at locations adjacent the swinging edge of the door and also adjacent a side edge thereof; to provide a latching means which will retain the door in partly closed position and move the same to fully closed position by further operation of the latching means; and to provide for safety and convenience in the operation of the latching means.

For a more complete understanding of the nature and scope of this invention reference may be had to the following description taken to-

2

gether with the accompanying drawings, in which:

Figure 1 is a view in front elevation of the door of a hopper for a hopper type car in which the present invention is embodied, the door being shown in pendant open position facing the opening with the hopper being shown between the center sill and side wall of a conventional type of railway car;

Figure 2 is a vertical sectional view taken through the door and hopper and on a line corresponding substantially to a line 2—2 of Figure 1;

Figure 3 is a fractional elevational view looking in the direction of the arrows on line 3—3 of Figure 2, showing so much of the hopper as necessary to show in elevation the latch keeper carried by the sloping floor;

Figure 4 is a frontal elevational view of a door and frame assembly, the view being shown with the door in closed and latched position;

Figure 5 is a vertical sectional view taken generally along the line 5—5 of Figure 4;

Figure 6 is a fractional view of the door and frame assembly shown in Figure 4 but showing the latch bar as positioned entering the zone of the main shoulder in its transition along the wedging incline to the main shoulder;

Figure 7 is a view similar to that shown in Figure 5 except that the door is shown in preliminary held position with the latch bar engaging the secondary shoulder;

Figure 8 is a top plan view of the latching bar;

Figure 9 is a view, in front elevation, of the latching bar shown in Figure 8;

Figure 10 is a top plan view of the door beam member;

Figure 11 is a view, in front elevation, of the door beam member shown in Figure 10; and

Figures 12 and 13 are end elevation views of the door beam member shown in Figure 11.

In the drawings, Figures 1 and 2, the invention is shown as applied to a so-called W type of hopper and to a door on one side of the center sill. The reference character 10 designates a center sill of a conventional railway car having a side wall 11 spaced therefrom with a hopper 12 therebetween.

The hopper 12 is formed by inner and outer side walls indicated at 13 and 14 respectively, a top sloping floor 15 and a lower floor 16 which slopes downwardly to an opening 17. Surrounding the opening 17 is a frame that is indicated generally at 18. It comprises a lower portion 19 which overlies the respective side walls 13 and

14 and a transversely extending portion 20 which underlies the sloping floor 16. Said lower portion 19 is preferably of angle shape having an outstanding wall 21. The upper part of the frame 18 includes a top beam member 22 from which hinge butts 23 project.

The hinge butts 23 carry hinge pins 24 which support hinge straps 25 at their upper ends. The hinge straps 25 are secured by rivets 26 to the door which is indicated, generally, at 27. The door 27 is preferably of trapezoidal form and of pan shape and it has a flange 28 around its edge which fits over and encloses the four sides of the frame 18 so as to provide a tightly fitting joint therebetween.

The door 27 is of the type which is adapted to be swung or lifted to closed position and latching means are employed to retain it in closed position. The latching means of my invention includes a latching bar 29, Figures 8 and 9, pivotally mounted at 30 on a door beam member which is indicated, generally, at 31 and shown in detail in Figures 10, 11, 12 and 13. Extending in opposite directions from the pivot 30 to the latch bar are arms 32 and 33, the arm 32 extending laterally outwardly beyond the inner side edge of the door 27 to engage with a shouldered keeper 34, Figure 2.

The shouldered keeper 34 is of angular form with a body portion 34a extending lengthwise parallel with the inner side wall 13 of the hopper 12 and a flange 34b which overlies the outstanding wall 21 of the frame 18. The wall 21 is coped out as indicated at 34c, Figure 1, for the accommodation of the body portion 34a and the respective parts are welded together as indicated at 34d, Figure 4, to form an integrated structure.

The opposite arm 33 extends towards the outer side edge of the door 27 and adjacent its outer end is provided with an outwardly projecting head portion 35. Intermediate the pivot 30 and the head 35 and preferably adjacent the latter there is provided a downwardly extending plunger 36 which extends towards and beyond the swinging edge of the door 27 for cooperation with a shouldered keeper 37, Figure 3. The shouldered keeper 37 includes a base portion secured to the lower edge of the floor 16 and the transversely extending portion of the frame 18 by rivets 38 and 39 and is formed with a hollow socket-like aperture 40 for receiving the latch plunger 36. The keeper 37 is located inwardly of the midsection of the opening 17 of the hopper 12 and in such proximity to the outer side wall 14 as to derive support therefrom.

The pivot 30 of the latching bar 29 is disposed on the door 27 to provide the arm 33 to be of greater length than the opposite arm 32 and such additional length combined with the additional weight provided by the head 35 and the plunger 36 operates to maintain the respective latching portions of the bar 29 in latching position, as shown in Figure 1, when the door 27 is in the open position.

The latching bar 29 is displaced from its normal latching position shown in Figure 4 during the door closing operation by the short arm 32 contacting and riding on an inclined runway surface 41, Figure 5, formed on the underside of keeper 34. The keeper 34 is provided with a secondary shoulder or ledge 42, Figure 7, which is disposed in advance of and to the rear of a main shoulder 43 and connected therewith by an inclined wedging surface 44 whereby, as the door 27 is moved to closed position, the arm 32 en-

gages with the secondary shoulder 42 and thereby is retained in partly closed position. The door 27 is wedged from partly closed to fully closed position by movement of the bar 32 as it rides in contact with and along the wedging surface 44.

The inner edge of the door is brought to a complete state of closure by contact between the arm 32 and the main shouldered part 43 of the keeper 34 before contact is effected between the plunger 36 and the shoulder 45 of the keeper 37. The plunger 36 is formed with a triangular shaped wedge portion 136, Figure 9, which operates as an entering wedge to the keeper 37 to force the swinging edge of the door 27 tightly closed. Inasmuch as the door closing operation is effected from a location adjacent the outer side of the door 27, there is a tendency for the inner side to lag slightly and consequently it is advantageous to force the inner side of the door 27 to fully closed position independently of the outer side.

The lengths of the respective arms 32 and 33 are so proportioned and the keepers 34 and 37 so related thereto as to permit the short arm 32 to move the inner end of the door to fully closed position with the latching bar 29 entering the final latching zone is illustrated in Figure 6 before contact is established between the plunger 36 and its associated keeper 37. In this manner the door 27 is moved from partly closed to fully closed position by a downward pull thereon which, being exerted outwardly of the hinge axis of the door 27, has the effect of exerting a turning movement to swing it to closed position. This condition is well illustrated in Figure 7 wherein the length of the turning moment arm is indicated at 46.

The latching bar 29 preferably is retained in latched position in the conventional manner by a pivotally mounted cam 47 which is adapted to be swung into the path of movement of the latching bar 29 as shown in Figure 4.

The door beam 31 which forms the support for the latching bar 29 and cam 47 is preferably of angle shaped formation with one wall 48, Figure 45, 50, secured to the body of the door 27 and the adjacent wall 49 outstanding at right angles therefrom. The beam 31 is provided with an upstanding wall 50 which in combination with the wall 48 constitutes a pair of walls between which the latching bar 29 is mounted and which support the pivot 30 thereof. The beam 31 is downwardly directed as indicated at 51, Figure 11, towards the inner edge of the door 27 in order to provide clearance for the latching arm 29 as it is swung downwardly to released position. The wall 48 is extended beyond the inner edge of the door 27 towards the keeper 34, as indicated at 52, to support the overhanging portion of the latch arm 32. Adjacent the inner edge of the door 27 there is provided on the beam 31 a guiding wall 53, Figures 11 and 13, which leads upwardly from the outer edge of the wall 49 to overlie the arm 32 and above the arm 32 it is integrally united with the rear wall 48 by means of 65 an integrally formed connecting wall 54. The latch arm 32 is thus braced and guided throughout its range of swinging movement. Similarly the outer end of the arm 33 is guided between spaced inner and outer walls 55 and 56, Figure 12, extending upwardly from the beam 31. The walls 55 and 56 also support the cam 47 and guide the same.

An aperture 57, Figure 12, is provided in the wall 49 of the beam 31 for the accommodation of the plunger 36 of the latching bar 29. Formed

integrally with the wall 49 and surrounding the aperture 57 there is a reinforcement 58. The reinforcement adjacent the body of the door 27 is extended downwardly as at 59 as far as the lower margin of the body of the door 27 in order to provide bracing and supporting backing for the plunger 36 of the latching bar 29.

The extreme outer end of wall 49 is provided with a foot rest in the form of a serrated surface 60, Figures 1 and 11, for the purpose of forming a purchase for an operator's foot when the door 27 is pedalled to closed position.

Fulcrums, as indicated at 61 and 62 in Figure 11, are provided to form rests for a removable operating bar 63, shown by broken lines in Figure 1, whereby in cooperation with the operating head 35 of the latching bar 29, the latter may be either forced home to latching position or moved to released position. The fulcrum 61 is in the form of an outward extension of the wall 49 on which the removable bar 63 is positioned as indicated in Figure 1.

In operation, assuming the door 27 to be in open pendant position as indicated in Figure 2, the operator places a foot on the serrated rest 60 and rocks the door 27 to and fro until it swings to closed position while the latch arm 32 is displaced by contact with inclined surface 41 of the keeper 34, whereupon it engages with the secondary shoulder 42 and the door 27 is retained in partly closed position as shown in Figure 7. The operator then bears down on the outer end of arm 33 causing the arm 32 to move along the inclined wedging surface 44 until such time as the arm 32 contacts the main shoulder 43 of the keeper 34 after which continued movement of the arm 33 forces the plunger 36 into the aperture 40 and thus into cooperating engagement with its associated keeper 37. The door 27 is then fully closed and latched. Thereafter the cam 41 is swung to secure the latching bar 29 against unlatching movement.

As will be noted by reference to Figure 2, the keeper 37 is situated well above the rail line as indicated at 67 thereby providing ample room for sidewise withdrawal of lading from beneath the opening 17 by the conventional conveyor method. It will also be noted that the plunger 36 of the latching bar 29 extends only a slight amount into the clearance limits of the door 27. In order to permit of the placement of the plunger 36 in a favorable position relatively to the swinging edge of the door 27, a certain portion of it is coped and indented as indicated at 68, Figure 1, for the purpose of straddling the keeper 37 when the door 27 is in closed position.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. Latch means for a door for closing the discharge opening of a railway car or the like where the door is hinged along its upper edge comprising, in combination, a latch bar pivotally mounted intermediate its ends along the swinging edge of said door thereby providing a pair of oppositely extending arms of different lengths the shorter of which extends beyond one side of said door while the longer extends toward but not beyond the other side of said door and has a de-

pending portion spaced from the pivot axis of said latch bar and in latching position projecting beyond the swinging edge of said door, an apertured keeper on said car along the lower edge of said door for cooperating with said depending portion by endwise downward movement thereof through the aperture to hold said door closed, a downwardly directed keeper on said car along said one side of said door for cooperating with said shorter arm by sidewise upward movement thereof to hold said door closed, and an inclined runway portion on said downwardly directed keeper for engaging said shorter arm during closing movement of said door to swing said latch bar and said depending portion carried thereby clear of said apertured keeper and into a position where, on further movement of said door, said depending portion is movable into said aperture.

2. Latch means for a door for closing the discharge opening of a railway car or the like where the door is hinged along its upper edge comprising, in combination, a latch bar pivotally mounted intermediate its ends along the swinging edge of said door thereby providing a pair of oppositely extending arms of different lengths the shorter of which extends beyond one side of said door while the longer extends toward but not beyond the other side of said door and has a depending portion spaced from the pivot axis of said latch bar and in latching position projecting beyond the swinging edge of said door, a keeper on said car along the lower edge of said door for cooperating with said depending portion by endwise movement thereof to hold said door closed, and a shouldered keeper on said car along said one side of said door for cooperating with said shorter arm by sidewise movement thereof to hold said door closed, said shouldered keeper having a main shoulder for engagement by said shorter arm to hold said door fully closed and a secondary shoulder spaced from said main shoulder for engagement by said shorter arm to hold said door partly closed and a wedging incline connecting said shoulders whereby movement of said door from partly to fully closed position is effected by movement of said shorter arm, the transition of said shorter arm from said secondary shoulder to said main shoulder being effected before said depending portion of said latch bar engages its keeper.

3. Latch means for a door for closing the discharge opening of a railway car or the like where the door is hinged along its upper edge comprising, in combination, a latch bar pivotally mounted intermediate its ends along the swinging edge of said door thereby providing a pair of oppositely extending arms of different lengths the shorter of which extends beyond one side of said door while the longer extends toward but not beyond the other side of said door and has a depending portion spaced from the pivot axis of said latch bar and in latching position projecting beyond the swinging edge of said door, an apertured keeper on said car along the lower edge of said door for cooperating with said depending portion by endwise downward movement thereof through the aperture to hold said door closed, a downwardly directed keeper on said car along said one side of said door for cooperating with said shorter arm by sidewise upward movement thereof to hold said door closed, and an inclined runway portion on said downwardly directed keeper for engaging said shorter arm during closing movement of said door to swing

7
 said latch bar and said depending portion carried thereby clear of said apertured keeper and into a position where, on further movement of said door, said depending portion is movable into said aperture; said downwardly directed keeper having a main shoulder for engagement by said shorter arm to hold said door fully closed, a secondary shoulder spaced from said main shoulder for engagement by said shorter arm to hold said door partly closed, and a wedging incline 10 connecting said shoulders whereby movement of said door from partly to fully closed position is effected by movement of said shorter arm, the transition of said shorter arm from said sec-

5

ondary shoulder to said main shoulder being effected before said depending portion of said latch bar engages its keeper.
